UNITED STATES PATENT OFFICE.

MALCOLM C. HARPER, OF EVANSTON, ILLINOIS.

TIME DAMPER MECHANISM.

No. 800,295.

Specification of Letters Patent.

Patented Sept. 26, 1905.

Application filed April 18, 1904. Serial No. 203,717.

To all whom it may concern:

Be it known that I, MALCOLM C. HARPER, a citizen of the United States, and a resident of Evanston, in the county of Cook and State of Illinois, have invented certain new and useful Improvements in Damper-Controlling Devices; and I do hereby declare that the following is a full, clear, and exact description thereof, reference being had to the accompanying drawings, and to the letters of reference marked thereon, which form a part of this specification.

This invention relates to damper-actuating mechanism for stoves or furnaces of that class embracing a clock mechanism like an ordinary alarm-clock and an actuating-weight, which is released by the clock and the movement of which when released effects the opening or closing of the damper or dampers.

The invention consists in the matters hereinafter described, and pointed out in the appended claims.

In the accompanying drawings, Figure 1 is a view in side elevation of a furnace, together with a damper-actuating mechanism embodying my invention. Fig. 2 is an enlarged detail section of the casing which contains the clock, taken on line 2 2 of Fig. 3, the clock and actuating-weight, with associated parts, being shown in side elevation. Fig. 3 is a plan section of the same parts shown in Fig. 2, taken upon line 3 3 of Fig. 2. Fig. 4 is a vertical section taken upon line 4 4 of Fig. 2. Fig. 5 is a detail vertical section taken upon line 5 5 of Fig. 4. Fig. 6 is a perspective view showing the rear face of the clock, the weight, and the detent-lever which holds the weight from movement and is acted upon by the clock. Fig. 7 is a view showing a somewhat different arrangement in the devices for communicating motion from the actuating-weight of the device to the furnace. Figs. 8 and 9 are side and face views, respectively, of the detent-lever and upper part of the weight-arm, showing a modified construction in these parts.

As shown in said drawings, A indicates a clock of the kind commonly called an "alarm-clock." Said clock need not have any alarm-bell attached, as the only part of the alarm mechanism used in the present instance is the spring-actuated mechanism which is commonly used to operate the alarm-bell hammer. As shown in the said drawings, A' is the winding-shaft of the spring-actuated mech-

anism, which is provided with a winding-crank α .

B designates a weight-supporting arm arranged generally in an upright position and pivoted at its lower end on a horizontal pivot pin or rod b . To the upper end of said arm B is attached a weight B'.

C designates a detent-lever which is pivoted between its ends to swing on a horizontal pivot c. Said detent-lever is provided at its end adjacent to the weight-arm B with a holding prong or tooth c', adapted for engagement with a shoulder b' on the said arm, the detent-lever being so arranged that when its end which engages the lever B is at the upward limit of its movement it engages the said shoulder b', and thereby holds the weight-arm in its upright position and the weight from falling, and when said end is depressed it will release the arm and weight to permit the descent of the weight through the swinging of the arm on its pivot. The parts are so arranged that when the weight-arm is engaged by the detent-lever C said arm will be slightly inclined from the vertical, with the center of gravity of the weight at the side of the pivot toward which the weight falls, so that the weight will be free to descend as soon as released. The end of the detent-lever C opposite that which engages the weight-arm B is connected with the winding-shaft A' of the alarm mechanism of the clock A in such manner that when the said winding-shaft is released through the action of the clock mechanism at a predetermined time the turning of such shaft will give motion to the detent-lever in a direction to release the weight.

The connection of the detent-lever with the winding-shaft may be made in various ways; but, as herein illustrated, the detent-lever is provided with a longitudinal slot c², and the crank-arm α on the winding-shaft A' is provided with a part α' , which is parallel with the shaft itself and passes through said slot c². As a result of this construction when the winding-shaft is released through the action of the clock mechanism and permitted to turn the detent-lever will be moved or oscillated, so as to release its opposite end from the lever B and permit the descent of the weight.

In addition to the parts described I also employ a spring-detent D, which is arranged in position to engage a projection or shoulder b² of the lever B when the said lever is swung past the position in which it engages the de-

tent-lever, and thereby holds the weight from falling when it is desired that the weight shall be held or locked from movement. In the particular construction shown the shoulder b' 5 for engaging the detent-lever C and the shoulder b'' for engaging the spring-holding detent D are formed on the weight at either side of the outer end of the arm B, the weight and arm being for convenience cast in one piece; 10 but said shoulders may be formed either on the weight or on the arm, as preferred, the effect being the same in either case.

For communicating motion from the weight to the damper or dampers a chain E is shown 15 as attached to the weight or its supporting-arm, said chain being preferably secured to the arm at a point between the weight and the pivotal point of the arm. Said chain passes upwardly over a guide-pulley F and 20 then horizontally over a second guide-pulley F'. In the particular construction shown the parts above described are mounted in a rectangular frame consisting of three uprights G G' G'', a top horizontal frame-piece G³, and 25 a bottom horizontal frame-piece G⁴. Side walls G⁵ and G⁶ are secured to the frame-pieces, so as to form a case or inclosure for the parts. The clock A is inclosed in a compartment formed by means of the two upper 30 right frame-pieces G G' and two horizontal pieces g g', which form the bottom and top walls of the inclosure or compartment and of which the piece g forms a shelf on which the clock rests. The compartment for the clock 35 thus formed is provided with a hinged door G⁷, which forms part of the wall G⁶ and covers the side of the compartment at which the winding-shaft projects, but which is wide enough to extend past the upright piece G' 40 and expose the end of the detent-lever C, which engages the weight B'. The clock A is shown as fitted in a hole made in the wall G⁵, so that the face of the clock will be visible from the exterior of the inclosure, while 45 at the same time the rear part of the clock and parts there located will be within the inclosure and will be protected from dust and dirt. Said detent-lever C is shown as passing through a hole in the upright G' and the 50 pivot c for the lever as being inserted in the said upright. The pivot b for the lower end of the lever is shown as made of staple form and secured to the lower horizontal frame-piece G⁴. The spring-detent D is shown as 55 attached to the side of the frame-piece G'.

As shown in Fig. 1, H is a furnace of ordinary construction having a draft-door H', which is hinged so as to swing on hinges at its upper edge, and a smoke-pipe H'', provided 60 with a damper I and a check-draft J.

The damper I is shown as pivoted on a horizontal shaft i, provided with a counterbalance-weight i' on an arm which extends upwardly from the shaft i and swings over said 65 shaft when the damper is turned from its open

to its closed position, or vice versa, and thereby tends to hold the same either in its open or closed position. Said shaft i also has a depending arm i'', by which the damper is actuated. The check-draft J is shown as consisting of a plate which is pivoted at its upper margin to the smoke-pipe and in connection with which is employed a bell-crank lever K, pivoted to the side of the pipe and having an arm k, which is adapted to engage 70 one of a series of teeth j on the damper and serves as a prop to hold the same open. Said bell-crank lever also has an arm k', through which the lever is actuated. In this instance the chain E after passing over the guide-pulley F' passes downwardly over a pulley F² and then horizontally to the smoke-pipe H'', where it is connected with the damper-lever i'' and the arm k' of the bell-crank lever J. In this instance, moreover, a chain 75 L is secured at its lower end to a draft-door H' and at its upper end to the ceiling, and said chain L is connected with the chain E at the point where the latter crosses the same. 80

In the operation of this device it is manifest that when the weight B' is released and falls from its vertical to its horizontal position tension will be exerted on the chain E, which will result in flexing the chain L, so as to lift or open the draft-door H'. The pull 90 on the chain E will also turn the damper I to open the same and swing the bell-crank lever K so as to release the check-draft J. 95

In Fig. 7 I have shown a somewhat different arrangement of the parts for operating the check-draft. In this instance the check-damper is located on one side of the smoke-pipe H'' and a lever M employed which is hung between its ends on a chain N, which forms a fulcrum for the lever and is attached at its upper end to the ceiling. Said lever M is arranged with one end over the free edge of the check-damper, with which it is connected by a chain or flexible connection, while its opposite end is provided with a weight M'. An actuating-chain O in this instance is connected with the weight M' and extends upwardly and is attached to a stationary object P. A chain Q extends above the same horizontally from the chain O to the chain E, said 105 chain Q being connected with the chain O between the ends of the latter. The weight M' is made sufficiently heavy to lift the check-damper and to hold the same normally opened; but when the actuating-weight B' is released 110 and falls the weight M' is lifted by the action of the chain O and the check-damper thereby permitted to close. This latter construction is a convenient one for use in applying the device to old furnaces inasmuch as it enables 115 the operating-lever to be easily placed or supported in any desired position necessary for operation whatever may be the location of the check-draft damper with respect to the operating device. 120

An important advantage is gained by placing the actuating-weight on an arm so arranged that the said arm stands in a nearly vertical position when the weight is lifted and held by the holding-detent C, for the reason that in this position of the weight-arm the weight exerts very little pressure on the holding-detent, and the latter may therefore be moved with very slight exertion of force or power by the clock mechanism. It follows that the weight may be very readily released; but after its release it acts with increasing force as it descends, reaching its maximum effect when nearly in a horizontal position, so that a weight of relatively small size will exert sufficient power to easily operate all the dampers of a furnace. Moreover, by attaching the actuating-chain to the weight-arm at a point between the weight and the pivot of the arm the effectiveness of the weight is increased, and by changing the point of attachment of the chain to the arm any desired amount of power may be obtained within the limits afforded by the gravity of the weight and the length of the arm in accordance with the necessity of any particular case, it being obvious that when the chain is attached to the arm at a point near the pivot the movement given will be less and the power will be greater, while if a greater movement and less power be required the chain may be attached near the extremity of the arm or even to the weight itself.

Figs. 8 and 9 show a construction which may be substituted for the spring catch or detent D above described for holding the weight out of action. As shown in said figures, R indicates a horizontally-arranged latch-lever, which is pivoted to the outer face of the weight-arm B and projects from the side face of said arm in position to engage the detent-lever C. Said latch-lever R is adapted to swing between lower and upper stop-lugs r r' on the arm B and to rest normally on the lower stop-lug r. The detent-lever C is provided in this instance in addition to the holding-tooth c' with a second holding-tooth S, located at the rear of said tooth c'. When in the use of this device the weight-arm B is swung to its uppermost position, the latch-lever R will engage the tooth S, which will hold the weight-arm from movement; but said tooth S being longer or higher than the tooth c' it will not be released from the latch-lever R if the detent-lever C be moved by the clock, so that the weight-arm will be positively held from movement by said parts. When, however, the parts are to be set for operation by the clock, the latch-lever R will be lifted over the longer tooth S and engaged with the tooth c', and then upon the actuation of the detent-lever by the clock the weight-arm will be released, as in the construction first described.

An important advantage of the construction shown in Figs. 8 and 9 is that in case the crank-arm of the winding-shaft should come to rest

in a position to hold the detent-lever C with its end which engages the weight-arm elevated then in the construction shown in the other figures the shoulder b² on said arm could not pass over the tooth c' and the weight-arm 70 could not be thrown into position to be locked out of action. When a pivoted latch R is used, the free end of said latch will under the conditions referred to rise or ride over the said tooth c' and permit the arm to be swung 75 upwardly or backwardly far enough to engage the tooth S. It follows from the above that the pivoted latch R will be useful whether the weight is held or locked by the spring-detent D or by the auxiliary tooth S on the de- 80 tent-lever.

I claim as my invention—

1. A draft-controlling device embracing a clock mechanism, a pivotally-supported arm provided with a weight, a detent-lever adapted to engage said arm when the weight stands nearly over the pivotal axis of the arm and which is operated by the clock mechanism, a damper-operating chain connected with said arm between the weight and the pivot of the 90 arm and a guide-pulley for the chain located above the level of the pivot of the arm. 85

2. A draft-controlling device embracing a clock mechanism, a pivotally-supported arm provided with a weight, a detent-lever operated by the clock mechanism adapted to engage the arm when the weight is nearly over the pivotal axis of the arm, a damper-operating chain connected with said arm between the weight and the pivot of the arm and a holding device which engages said weight when swung upwardly past the point at which it is engaged and held by said detent-lever and which is adapted to hold said weight out of engagement with said detent-lever. 100 105

3. A draft-controlling device embracing a clock mechanism, a pivotally-supported arm provided with a weight, a detent-lever operated by the clock mechanism and provided with a shoulder adapted to engage said arm when the weight is nearly over the pivotal axis of the arm and with a second shoulder located in position to engage the said arm when the weight is swung upwardly past the point at which it is engaged and held by the first-named shoulder of the detent-lever, and a damper-operating chain connected with said arm. 110 115

4. The combination with a gravity-closing damper, of a controlling device embracing a clock mechanism, an arm provided with a weight, a detent-lever operated by the clock mechanism adapted to support the weight in a position nearly over the pivotal axis of the arm, an upright chain connected at its lower end with the damper and at its upper end with a stationary object, and a chain connected with the said arm and which is connected with and leads laterally from the upright chain between the ends of the latter. 120 125 130

5. The combination with a gravity-closing check-draft, of a clock mechanism, a rising-and-falling weight, a detent-lever operated by the clock mechanism and which holds the
5 said weight in its elevated position, a horizontally-arranged lever which is pivoted between its ends, is connected at one end with the check-damper and provided at its opposite end with a weight which tends, by its
10 gravity, to lift said damper to open the same, and a chain connected with said rising-and-falling weight and with the weighted end of the horizontal lever and operating to lift said weighted end of the horizontal lever when
15 the rising-and-falling weight descends.

6. A draft-controlling device embracing a clock mechanism, a pivotally - supported weighted arm, an arm provided with a weight which is adapted to rise and fall through the
20 swinging of the arm on its pivot and when, in its elevated position, stands nearly over the pivot of said arm, a detent-lever operated by the clock mechanism and a gravity-actuated pivoted latch-lever on the weighted arm

adapted for engagement with said detent- 25 lever.

7. A draft-controlling device embracing a clock mechanism, a pivotally - supported, weighted arm adapted to swing from a horizontal into a nearly upright position, a detent-lever having a tooth adapted to engage said arm when in its nearly upright position and which is connected with and operated by the clock mechanisms, and a second tooth on the detent-lever and a pivoted latch-lever on 30 the weighted arm adapted for engagement when said arm is raised and thrown rearwardly past the position in which it is engaged by the first-named tooth on said detent-lever.

In testimony that I claim the foregoing as my invention I affix my signature, in presence of two witnesses, this 15th day of April, A. D. 1904.

MALCOLM C. HARPER.
